ATTORNEY.

UNITED STATES PATENT OFFICE.

GOTTLIEB D. WILMS AND JOHN H. STEIGER, OF PATERSON, NEW JERSEY.

SHUTTLE TENSION.

1,400,397.

Specification of Letters Patent. Patented Dec. 13, 1921.

Application filed September 3, 1921. Serial No. 498,355.

To all whom it may concern:

Be it known that we, GOTTLIEB D. WILMS and JOHN H. STEIGER, citizens of the United States, residing at Paterson, in the county 5 of Passaic and State of New Jersey, have invented certain new and useful Improvements in Shuttle Tensions, of which the following is a specification.

This invention relates to shuttles, and particularly to shuttles of the narrow-ware class, the principal objects being (1) to provide a shuttle with a tension means which will allow the wound package to rotate with perfect freedom, to deliver the filling, when 10 the filling is subjected to draft but which will take up any slack that tends to form and also hold the wound package stationary immediately the draft ceases, thus to insure the proper laying of the filling in the warp 15 20 25 30 35 40 45 50 55 60 65 70 75 80 85 90 95 100 105 110

quill *g* of the wound package *g'*, the same being of a general form common in narrow-ware shuttles, *i. e.*, with one end *f'* bent off; when the other end is fitted into the socket end *f'* may be slipped into the notch *e*, to be there retained in a way to be explained.

In the boss *d* is arranged the stem *h'* of a fork *h*, which may be adjusted longitudinally therein and in a bore *i* and there held by a riveted pin *j* adapted to penetrate any one of a series of holes in the stem and a corresponding hole in the boss. In this fork is pivoted a brake member *k*, its axis of movement being in a vertical plane. The brake member is adapted to bear against the flat or square-cut end of the quill, and in order to admit or permit withdrawal of the spindle *f*, which penetrates it, said brake member has a suitable recess *k'* (Fig. 5) which enters it from its upper edge, in registry with the plane of movement of the spindle, when assembling it with or removing it from the shuttle body. By adjusting the fork in the boss *d* quills of various lengths may be accommodated in the shuttle. In bores converging from the base of the shuttle toward the opening formed by its bow are arranged spiral springs *l l'* suitably anchored at their outer ends and at their inner ends having attached thereto the thread guides or eyes *m m'*. Guide or eye *m'* is connected with the brake member by a light cord or other flexible connection *n* which passes through a centrally located guide or eye *o* preferably pivoted (as by being wired) to the shuttle bow; through the medium of this cord the spring-pulled eye *m'* normally tends to hold the brake member in braking contact with the end of the shuttle package, to wit, of quill *g*. Pivoted (as by being wired) to the shuttle bow are two other thread guides or eyes *p p* arranged one on each side of the central fixed or delivery thread guide or eye *q* in the shuttle bow. The thread or filling *A* extends from the filling package through the right-hand guide *p*, guide *m'*, left-hand guide *p*, guide *m* and finally out through guide *q*. It will thus be seen that when the draft comes on the filling it acts to draw the guides *m m'* together, the result of which is that the cord and consequently the pull on the brake member is relaxed, allowing the package to rotate freely on the spindle so as to deliver the filling, and when the draft

In the drawing,

Figure 1 is a plan of one form of the improved shuttle;

Fig. 2 is a section on line 2—2, Fig. 1;

Figs. 3 and 4 illustrate the spindle-lock 40 shown in Fig. 1, being sections on line 3, Fig. 1;

Fig. 5 is a section on line 5—5, Fig. 1;

Fig. 6 is a fragmentary plan of another form of the improved shuttle; and

Fig. 7 is a section on line —7, Fig. 6.

a designates the body of a shuttle, here of the usual bow type. At one side of and within the bow is suitably secured a plate *b*, which may be regarded as a part of the body or fixed part of the shuttle, the same having a socket *c* and horizontally alined with the socket an inwardly projecting boss *d*. Opposite the socket and at the other side of the bow is the usual notch *e*. *f* designates 50 55 60 65 70 75 80 85 90 95 100 105 110

ceases spring l' becomes immediately active again to subject the package to the braking action of the brake member.

5 Into the body of the shuttle so as to project into the notch e and in the same direction as the end f' of the spindle, and also so as to lie in the same plane as the spindle moves in entering it into and removing it from the notch, is driven a stud r , the projecting end thereof being canted toward the spindle and having its extremity at the side adjoining the spindle beveled off. The stud is somewhat elastic and when the bent-off end of the spindle, its other end being seated in the socket c , is entered into notch e and forced against the beveled or cam extremity of the stud the latter is sprung back and thereupon comes to bear frictionally against said bent-off end, so that the spindle is securely held in place and can only leave the notch e when forced out by hand.

10 In the form shown in Figs. 6 and 7 the body of the shuttle includes an angular metal frame s suitably secured in the bow opening, the oppositely arranged bent-off ends s', s'' thereof reposing against the sides of said opening. The end s' has a socket t for the spindle u and it has also a boss v to receive the stem w' of the fork w in which 15 the brake member x , to bear against the end of the quill y , is pivoted, so much of that 20 form of our invention which is now being described being the same as that already described except for the frame s and the means 25 for adjusting stem w' which in the present 30 construction takes the form of a set-screw z tapped into the boss and bearing against the stem. The other bent-off end s'' overlies 35 the notch 2 (corresponding to notch e) 40 which receives the bent-off end of the spindle and itself has an upwardly open notch 45 $2'$ to receive the spindle. On the end s'' is a plate-spring 4 secured to the base-portion

of the frame s and has a recess $3'$ formed in its outer edge which is adapted to receive the spindle and coat with the outer side of the notch $2'$ to retain the same in said notch, said outer side of the notch and the outer 50 edge of the keeper being beveled so as to form a convergent approach $4'$ to the recess $3'$. When the spindle is entered into notch 2 and is forced into the approach $4'$ it cams back the keeper, which then springs back 55 and securely holds the spindle until the keeper is again manually pressed back. The outward limit of movement of the keeper is afforded by a stop 5 formed in effect by thickening the extremity of the end s'' . 60

Having thus fully described our invention, what we claim as new and desire to secure by U. S. Letters Patent is:—

1. In combination, a supporting structure including the shuttle body, a spindle supported at its end portions in said structure, a plate movable longitudinally of and in said structure and arranged in a plane crossing the axis of the spindle and adapted to bear against one end of a package arranged 70 on the spindle, said spindle being removable from said structure transversely of itself and in a definite plane and the plate having a lateral notch opposite the spindle and registering with the plane in which the spindle 75 is thus removable, and spring means for holding the plate against the package.

2. In combination, the body of a shuttle having a projecting arm and a notch therein and also a socket opposite the notch, a spindle stepped in the socket and tiltable therein into and out of the notch, and a slide on the arm normally spring-held in position to oppose tilting movement of the spindle out of the notch when the spindle is received 85 therein.

In testimony whereof we affix our signatures.

GOTTLIEB D. WILMS.
JOHN H. STEIGER.
